Application October 6, 1932, Serial No. 636,611

5 Claims. (Cl. 202—36)

This invention relates to an improved method and apparatus for heating carbonaceous materials under such temperatures and conditions as will yield the greatest amount of valuable materials or substances such as condensates, a considerable carbon residue, and certain gases;—and this under maximum thermal efficiency and minimum operating costs.

By carbonaceous materials we refer to such substances as coal, lignite, wood, oil shale, coal tar pitch, pitch, and any other material that when heated yields certain of the substances or bodies just above mentioned.

By condensates we mean all the condensable volatile matter resulting from the distillation of the above named materials.

By gas we mean such substances as do not liquefy under normal conditions.

The invention relates more particularly to a preferred method of forming charges of material, such charges having preformed channels therein through which the gaseous treating medium is drawn.

In our application Serial Number 418,612, filed January 4, 1930, we have claimed broadly the method of treating solid carbonizable material to distill and carbonize the same, wherein a charge of the material was formed with a plurality of spaced channels extending therethrough, subjecting the exposed surface of the charge to the action of a fluid heating medium and drawing such medium, together with the distillates evolved in the treatment of the charge, through the channels in the charge and in direct contact with the material from which the charge is formed. The present invention has to do with the means whereby such charges may be formed in receptacles to be placed in a retort or in forming the charge in the retort proper.

The charges thus formed may be introduced into a retort for treatment, such for instance as is shown in our copending application, Serial No. 685,779, filed August 18, 1933, as a division of our application Serial No. 636,612, filed October 6, 1932, or as of even date herewith.

In the drawings:

Fig. 1 is a vertical sectional view of a retort with the channel-forming tubes placed therein, said tubes being illustrated as filled with inert material;

Fig. 2, a similar view wherein the spaces between the channel-forming tubes have been partially filled with coal or other carbonaceous material to be treated;

Fig. 3, an enlarged detail view showing a por-

tion of the tubes and the plate employed for closing the space intermediate the tubes while the tubes are being filled with inert material;

Fig. 4, a like view showing the cap or die plate which closes the upper ends of the tubes when the material is being fed inwardly between the tubes;

Fig. 5, a detail sectional view of the lower portion of the tubes and the perforate supporting diaphragm underlying said tubes;

Fig. 6, an enlarged detail view of one side of the retort showing the upper portion of the completed charge;

Fig. 7, a horizontal sectional view taken on the line VII—VII of Fig. 1;

Fig. 8, a like view taken on the line VIII—VIII of Fig. 2 with portions of the supporting frame for the tube covering caps removed or broken away;

Fig. 9, a fragmentary detail view of the supporting diaphragm above referred to;

Fig. 10, a perspective view of one of the charge-receiving receptacles;

Fig. 11, a like view of one of the perforate receptacle bottoms;

Fig. 12, a detail fragmentary perspective view of means employed to introduce channeling material into the pan or receptacle preparatory to filling the body of the pan with the material to be coked;

Fig. 13, a similar view of dies or closure caps for the upper ends of the tubular members shown in Fig. 12 employed preparatory to filling the pan with the material to be coked;

Fig. 14, a transverse vertical sectional view of one of the pans, the removable bottom thereof, tubes or tube closures, a portion of the figure to the right and left, showing the material to be coked and the spacer material in position; and

Fig. 15, a transverse sectional view showing the pan with the material therein, the material and the channeling or spacing material being shown in their final position.

As above indicated, the method of forming the charge to be treated may be employed directly in a retort or may be employed to form the charge within a receptacle, which receptacle is thereafter introduced into a retort for treatment of the charge.

Referring first to Figs. 1 to 9, both inclusive, wherein the charge is formed within a retort and a batch method employed, 1 denotes the retort having a removable bottom 2 above which, and standing in a spaced relation thereto, is a perforate diaphragm or support 3 having a grid-like

form, as shown in Fig. 9, or other suitable form which will allow a gaseous medium and products produced in the treatment of the charge to pass downwardly therethrough.

5 The member 3 is mounted for sliding movement in and out of the retort and will preferably be actuated through the medium of a hydraulic cylinder 4. An off-take 5 opens into the chamber in the lower portion of the retort above the bottom 2, said off-take being connected with a suitable exhauster (not shown).

10 The upper portion of the retort is provided with a closure 6 and a plurality of burners 7 spaced away from the cover 6 lie above the normal level of the charge. Any suitable fuel may be employed in conjunction with said burners.

15 To place a charge within the retort having pre-formed channels extending therethrough and through which the gaseous or fluid heating medium will be drawn, the following means may be utilized. A series of tubes 8 are interconnected and held in vertical position and in horizontally spaced relation by cross rods or bars 9 which in turn are connected to a frame-work 20 25 10, shown in the instant case as rectangular to fit within the retort. The tubes are of such length that when the frame 10 comes to rest upon a shoulder or projection 11 extending inwardly from the wall of the retort the ends of the tubes stop short of the charge-supporting 30 35 grid or element 3. This relationship of the tubes to the grid is best shown in Fig. 1 wherein the tubes are shown as filled with solid granular material infusible at the temperature employed, such as coke formed from a previous run upon a charge of coal (when coal is being treated). At such time, or when the tubes are being filled, the spacers between the tubes are closed off by a plate 12 having openings 13 therein which register with the openings in the upper ends of the tubes. This plate rests upon the upper ends of the tubes and is of such dimension as to extend from wall to wall of the retort.

40 45 Where the tubes stop short of the removable bottom 23 of the charge-receiving receptacle, or retort as the case may be, the channel filling or forming material will spread out laterally to a certain degree, and thus insure that there will always be a passage downwardly through the grate-like member 3 or the openings in the false bottom 23, as the case may be. Otherwise, the coal or other material to be treated might close off the openings and prevent downflow of the heating medium through all the channels alike. 50 55 Where the false bottom is formed from a series of laterally spaced bars, as in our copending application Ser. No. 685,779, and supporting bars are introduced therebetween to support the charge while the false bottom is lowered, the 60 65 outspreading of the channel forming material is essential as the bottom surface of the charge may, of course, be disrupted to a slight degree.

70 When the tubes are filled, as shown in Figs. 1 and 3, the plate 12 is removed and the upper ends of the tubes are then closed by cap pieces or dies 14 which are interconnected with each other by rods 15. Said rods are connected at their outer ends or extremities to a frame 16, which when positioned as shown in Figs. 2 and 4 brings the cap pieces in alignment and directly over the upper ends of the tubes 8, the frame coming to rest upon the underlying tube-supporting structure.

75 The space between the tubes 8 is then filled with the material to be treated, say for instance

coal, the upper level of the coal being brought approximately to the level of the underside of the ledge 11. When this is accomplished the cap-carrying frame is lifted out of the retort and the tube-carrying frame is gently elevated stripping the tubes from the charge and allowing the relatively fine granular material within the tubes to spread and fill up the spaces occupied by the withdrawn tubes. This results in the upper surface of the charge being substantially level over its entire surface, as best shown in Fig. 6.

20 The cover of the retort is then closed and secured and the burners 7, which have been lighted, supply the necessary heat to the charge to convert it. The gas passing downwardly through the pre-formed channels is evenly distributed throughout the entire mass. It will of course be appreciated that molten metal or other fluid heating medium may be employed in place of gas.

25 When the process is first started the greatest heat of course obtains in the upper portion of the charge where the material is converted into coke, if coal is the material undergoing treatment. The heating gases, and those evolved in the treatment of the material, are drawn downwardly through the permeable channels and the material is first gradually heated and then converted into coke.

30 35 By the utilization of the substantially evenly spaced permeable channels a large surface area is exposed to the action of the gaseous or other heating medium and furthermore no irregular channeling of the material by the gaseous medium obtains as frequently happens when a charge is placed in a retort and the gaseous medium drawn or forced therethrough. Moreover, by subdividing the charge with the channels the heating medium has an opportunity to impart its heat not only to the surface but allows a quick penetration of the heat to the entire charge. Thus conversion takes place rapidly and evenly.

40 45 In Figs. 10 to 15 there is illustrated means for forming a pre-channelled charge within a receptacle which may be introduced into a retort. Such a receptacle is particularly applicable for use in an apparatus as set forth and described in our copending application Serial Number 636,-610, filed October 6, 1932, and more particularly in conjunction with the apparatus shown in our copending application Serial No. 685,779, filed August 18, 1933, wherein the receptacles with the pre-formed charges therein are introduced successively into the retort and are discharged therefrom in an empty condition, the converted material having been removed from the retort.

50 55 The receptacle may be of any desired form and in Fig. 10 a rectangular receptacle 20 is shown, said receptacle having vertically disposed guideways 21 and 22 at one end thereof. The receptacle may be strengthened in any desired manner and the removable bottom 23 is designed to fit closely therein and is sustained upon members 24 and 25 secured to the inner face of the lower portion of the receptacle.

60 65 The perforate bottom 23 is shown as provided with a pair of lugs or fingers 26 and 27 which pass into the guideways 21 and 22 when the bottom 23 is placed over the receptacle. These fingers of course are not essential to the present invention but are of utility in connection with the apparatus set forth in our copending application, Serial No. 636,610, just mentioned. In other words, insofar as the present invention is

concerned any form of receptacle may be employed so long as it has a perforate bottom.

With a view of forming pre-formed channels of material, infusible at operating temperatures, within the receptacle, horizontally spaced tubes, as 28, interconnected to each other and to a frame 29 by cross bars 30 are employed. Said frame will preferably be formed of angle iron and of such dimensions that when placed upon the upper edge of the receptacle 20 it will rest thereon, as best shown in Fig. 14, with the lower ends of the tubes slightly elevated from the bottom 23. The tubes 28 are then filled with granular material, such as coke produced as the result of the previous run.

It will be appreciated, of course, that inasmuch as the material which is introduced into the tubes 28 is granular and infusible at the operating temperatures employed, they remain open, or in other words, free to the passage of the products of combustion and gases which are introduced into the retort or evolved from the material undergoing treatment; this at all times.

After the tubes are filled their upper ends are covered by a series of caps 31 connected to a series of cross bars 32, which latter in turn are connected to a rectangular frame 33. The receptacle is then filled with the material to be treated, as for instance coal, the level whereof is somewhat below the upper edge of the receptacle and below the upper ends of the filled tubes (see Fig. 14). When this is effected the frame carrying the cap pieces is removed and then the tubes are gradually withdrawn by elevation of the frame 33.

As the tubes are withdrawn from the receptacle the granular material therein will spread laterally and thus fill the spaces voided by the tubes. This results in the production of a substantially level upper surface upon the charge with the upper ends of the pre-formed channels fully exposed. The position of the charge within the receptacle is then as shown in Fig. 15 with a series of channels filled with infusible material extending from the upper to the lower faces of the charge and evenly spaced throughout the mass of the charge.

It is, of course, manifest that instead of employing tubes which are withdrawn from the charge, tubes of combustible material, such for instance as card-board, may be utilized in forming the channels. In other words, the tubes will be positioned within a retort or receptacle in spaced relation, the tubes being filled with spacer material and the space about and around them thereafter filled with the material to be treated.

In the claims where the term "receptacle" is employed it is to be understood as referring to a retort as shown in Figs. 1 and 2 or to a pan or receptacle as shown in Fig. 10, unless the wording of the claim renders it specific to a retort or to a receptacle as such.

While we have described first the filling of the tubes and then surrounding them with the material to be treated, it will be apparent that the tubes may be filled last and then withdrawn from the charge. Under such operation the tubes would be made of such a length as to rest upon the perforate support so as to insure the extension of the inert material entirely through the mass.

It will, of course, be appreciated that the tubes may be of any desired cross sectional area and of any conformation or outline in cross section. It

will also be understood that the channels, while shown as vertically disposed, may be placed horizontally by orienting the receptacle in which the charge is formed, and that the fluid heating medium may be withdrawn from either end of the same under either disposition of the channels.

What is claimed is:

1. That method of forming a charge of solid carbonizable material with a view of subjecting the same to the action of a fluid heating medium to distil and carbonize the same, which comprises placing a series of horizontally spaced, vertically disposed open-ended tubes within a receptacle, said tubes terminating close to but short of the lower end thereof; filling the tubes with a permeable material infusible under the action of the heating medium which is at a temperature to distil or carbonize the charge; filling the receptacle about said tubes with the material to be treated; and, finally, withdrawing the tubes, thereby forming a plurality of spaced channels defined by the permeable material opening at opposite faces of the charge, with the last named material outspread at the lower ends of the channels.

2. That method of forming a charge of solid carbonizable material with a view of subjecting the same to the action of a fluid heating medium to distil or carbonize the charge, which comprises placing a series of laterally spaced, open-ended, vertically disposed tubes within a receptacle; filling said tubes with a granular material infusible under the action of the fluid heating medium which is to be employed; filling the remaining space in the receptacle with the material to be treated; and finally withdrawing the tubes, leaving the infusible material within the charge and extending therethrough from opposite faces thereof.

3. That method as set forth in claim 2, wherein the lower ends of the tubes which are placed in the receptacle stop short of the bottom thereof, whereby the infusible material spreads laterally with reference to such ends prior to the placement of the material to be treated.

4. That method as set forth in claim 2, wherein the lower ends of the tubes which are placed in the receptacle stop short of the bottom thereof, whereby the infusible material spreads laterally with reference to such ends prior to the placement of the material to be treated, the upper ends of the tubes being covered during the filling of the receptacle with the material to be treated.

5. That method of forming a charge of solid carbonizable material with a view of subjecting the same to the action of a fluid heating medium to distil and carbonize the same, which comprises placing a series of horizontally spaced, vertically disposed, open-ended combustible tubes within a receptacle, said tubes terminating just short of the bottom of the receptacle; filling the tubes with a permeable material infusible under the action of the heating medium which is at a temperature to distil or carbonize the charge; filling the receptacle about said tubes with the material to be treated, thereby forming a plurality of spaced channels defined by the infusible permeable material opening at opposite faces of the charge, with the last named material outspread at the lower ends of the channels.
